CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

SPRING AIR-GUN.

1,136,470.

Specification of Letters Patent. Patented Apr. 20, 1915.

Application filed June 21, 1913. Serial No. 775,092.

To all whom it may concern:

Be it known that I, CHARLES F. LEFEVER, a citizen of the United States of America, residing at Plymouth, in the county of Wayne and State of Michigan, have invented certain new and useful Improvements in Spring Air-Guns, of which the following is a specification, reference being had therein to the accompanying drawings.

10 The invention relates to air guns and comprises various features of construction as hereinafter set forth.

In the drawings: Figure 1 is a side elevation of the gun; Fig. 2 is a similar view partly in longitudinal section; Fig. 3 is a view similar to Fig. 2, showing the parts in a different position of adjustment; Fig. 4 is a sectional perspective view of the power storage mechanism; Fig. 5 is a cross section 20 thereof on line $y-y$ Fig. 2; Fig. 6 is a section on line $x-x$ Fig. 1; Fig. 7 is a perspective view showing the barrel and stock detached; Fig. 8 is a plan view of a portion of the barrel detached; Fig. 9 is a section showing the arrangement of the trigger safe mechanism; Fig. 10 is a horizontal section through the barrel and spring abutment; Fig. 11 is an elevation showing the means for releasing the spring from the abutment; 30 Fig. 12 is an end elevation of the barrel; and Fig. 13 is a longitudinal section through the actuating handle for the pump mechanism.

A is the stock of the gun, B the frame and C the barrel.

35 D is an actuating member for storing the power, which is slidable longitudinally of the barrel similar to the action of a so-called pump gun.

It is one of the objects of the invention to 40 obtain a knock-down construction in which the barrel may be separated from the stock and frame without the detachment or disarrangement of any of the parts of the mechanism. To this end all of the mechanism employed in storing the power is permanently mounted upon the barrel, the trigger, 45 sear and safe alone being upon the frame. This permits of taking down the gun by merely removing a single pin or fastening 50 device and then sliding the barrel out from engagement with the frame.

Take-down feature.—In detail, the barrel C has arranged therein an abutment E which 55 engages a slot F in the upper side of the barrel, and is provided with a downwardly

projecting ear E' extending through a slot in the lower side of the barrel. This ear E' has a segmental bearing E² on its forward side which registers with alined apertures G and G' in the opposite sides of the frame B. 60

H is a tapered pin passing through the alined apertures G G' and provided with a threaded end H' which engages corresponding threads in the aperture G'.

In rear of the abutment is a portion C' 65 of the barrel which telescopically engages the frame and is provided on its rear end with wedge-shaped bearings C², which engage a cross pin I in the rear of the frame. Thus when the barrel is slid into engagement with the frame, the bearings C² will pass into engagement with the pin I, and at the same time the segmental bearing E² will register with the apertures G and G'. The tapered pin H is then inserted and by screwing 70 the threaded portion of this pin into the aperture G' the tapered portion will be drawn against the segmental bearing E², forcing the barrel slightly rearward and the wedge-shaped bearings C² into firm engagement 75 with the pin I. Thus the barrel and frame will be securely fastened and the wedge-shaped bearings will take up all lost motion. 80

Power storage mechanism.—As above 85 stated, all of the mechanism for storing the power is mounted upon and detachable with the barrel. This mechanism, in detail, comprises the slide or hand-grip D which is mounted upon a rod J arranged 90 parallel to the barrel and beneath the same. This rod is preferably secured in position by being provided at its rear end with an inwardly-bent portion J' engaging an aperture in the barrel and notched at J² to 95 form a locking engagement therewith. The forward end of the rod J engages a bifurcated clip J³, which has a socket portion for receiving the rod and a pair of wings 100 for embracing the barrel. Intermediate this portion is a clamping screw J⁴, by means of which the parts may be securely held in position. The hand-grip D is connected with a toggle lever adapted to actuate the plunger against the tension of its spring. This 105 toggle lever preferably comprises links K and K' of sheet metal, and bifurcated to embrace the rod J and to normally conceal the same. The forward link K is pivotally attached at K² to the hand-grip D, while 110

the rear link K' is provided with an inwardly-projecting portion K³ which is fulcrumed upon a pin L in the upper portion of the barrel. This pin passes through a bearing in the abutment E and forms an additional means of securing the latter in position. The link K' is bifurcated to embrace the abutment and is held in central position by engaging slots L' in the upper portion of the barrel upon opposite sides of said abutment. The pin L is placed as high in the barrel as possible and the latter is slotted for its insertion, while the ends of the pin are rounded off to conform to the cross section of the barrel. There is also provided a key L² which engages a central slot in the abutment and a notch in the pin L, so as to hold the latter both from lateral displacement and from rotation, while a laterally-projecting portion L³ on said key closes the slot in the abutment when the parts are in position. The link K', as just described, forms in effect a bent lever having a laterally-extending portion K³ and the main portion which extends parallel to the barrel. Pivotal secured to this laterally-extending portion K³ is a link M normally in acute angular relation to the portion K³ and provided at its free end with a cross pin M'. Both the link M and portion K³ extend into a slot in the lower side of the barrel, which permits of longitudinal movement, while the pin M' engages with a notched bearing N in the plunger shank N' within the barrel. The pin M' also extends sufficiently to contact with the lower portion of the barrel upon opposite sides of the slot, thereby forming a guide which prevents disengagement from the barrel when out of engagement with the notch N. The shank N' is bifurcated to embrace the abutment E and the bifurcated portion K³ of the link K' and extends forward to the plunger N². This plunger fits a portion of the barrel constituting the air compression chamber, and a spring O is arranged between the plunger and the abutment E.

With the parts just described, whenever the hand-grip D is drawn rearward on the rod J, the links K and K' will be bent downward owing to the fact that the pin K⁴ connecting said links is below the center line of the pivots K² and L. This will cause the toggle links formed by the portion K³ of the link K' and the link M to be straightened, and in so doing the shank N' is forced backward by the pin M', drawing rearward the plunger and compressing the spring O, as shown in Fig. 3. During the movement the straightening of the toggles constantly increases the power of the leverage so that the spring is compressed with comparative ease. At the completion of the rearward movement the shank N' engages with the sear which holds it from re-

turn when the hand-grip D is moved forward. When the hand-grip is returned to its forward position, the links K and K' are prevented from dropping downward again by a lock formed by registering indentations therein, as shown at K⁵.

For convenience in assembling and disassembling the parts of the mechanism, provision is made for relieving the tension of the spring from the abutment when the latter is to be removed. This is accomplished by forming an aperture P in the barrel, and also apertures P' in the shank, which may be registered with said apertures P. This will permit of inserting a pin P² into the apertures P' and through a recess P³ in the abutment, locking the shank to the spring and relieving the pressure of the spring on the abutment so that the latter may be readily detached.

The trigger Q is pivotally mounted within the frame B upon the pin I, and is preferably formed of sheet metal bent to form a bifurcated bearing upon said pin. To prevent accidental discharge of the gun when the hand-grip D has not been fully returned, a trigger safety device is arranged within the frame, preferably consisting of a lever member R pivoted at R' and under tension of a spring R². The rear end of this lever is bent to extend laterally at R³ and in one position of adjustment its lateral extension is in the path of lugs Q' on the trigger, which will prevent the latter from movement. Thus as shown in Fig. 9 the forward end of the spring R² is rigidly secured to the lever R, while the opposite end of the spring is arranged beneath the pin I. When the parts are as shown in full lines in Fig. 9 the spring R² is slightly bowed, since the pin M' bears upon the forward end of the lever R, holding the forward end of the lever downwardly sufficient to raise the laterally-bent portion R³ out of the path of the lugs Q' and the trigger, but during the power storing operation the pin M' passes into engagement with the cutaway portion of the lever R, which allows the spring to straighten, thereby lifting the forward end of the lever, which will lower the laterally-extending portion R³ into the path of the lugs Q', as shown in dotted lines in Fig. 9. When, however, the hand-grip is returned to normal position the pin M' will, as before stated, bear upon the lever R so as to move it out of the path of the lugs Q', thereby releasing the trigger. The sear S is formed of a member separate from the trigger and provided with a hook S' which engages the bearing N. A single spring T bears against the sear and abuts against the end of the stock, being held from displacement by engaging a socket T' in said stock and a lug T² on the sear.

The frame of the gun is formed of sheet

metal bent into a U-shaped section having a cylindrical top portion and parallel sides, which forwardly of the trigger guard terminate in inwardly and downwardly-extending flanges, the latter embracing the link K'. In rear of the trigger guard the parallel sides are bent inwardly as at a² (see Fig. 5). The trigger guard U is also formed of sheet metal and is separable from the frame B, being engaged therewith by having a portion embraced by the downwardly-extending flanges and notched to engage a pin U². The rear of the guard has outwardly bent lugs U³ resting upon the flanges a².

V is an adjustable sight formed by a sheet metal member having downturned lugs V' forming a pivot bearing for a pin V², while the frame has upwardly struck flanges V³ between which the member V is placed and to which the pin V' is attached.

V⁴ is a set screw engaging the member V and bearing against the frame and V⁵ is an upwardly-bent portion of the member V notched to form the sight. A spring V⁶ is attached to move the plate V in one direction, while the set screw adjusts it in the opposite direction. Thus, by merely turning the set screw, the notched sight V⁵ may be raised or lowered.

The gun constructed as described is inexpensive to manufacture and thoroughly mechanical in all its details, while in appearance it closely simulates the powder pump gun.

What I claim as my invention is:

1. In a gun, the combination with a barrel and frame detachably telescopically engaging each other, of a power storage mechanism mounted upon and detachable with said barrel.

2. In a gun, the combination with a barrel and frame detachably telescopically engaging each other, of a power storage mechanism mounted on said barrel and detachable therewith, and a sear mounted on said frame for coöperation with said power storage mechanism.

3. In a gun, the combination with a barrel and frame telescopically engaging each other, of a power storage mechanism comprising a plunger, a compression spring, an abutment and a lever mechanism for retracting the plunger and compressing the spring, all mounted upon said barrel and attachable and detachable as a unit therewith.

4. In a gun, the combination with a barrel, of a frame having a cylindrical socket for telescopically receiving the end portion of the barrel, a lug projecting downward from said barrel, spaced flanges in said socket member between which said lug is inserted, and a pin passing through said spaced flanges and engaging a bearing on said lug

to retain said barrel in engagement with said frame.

5. In a gun, the combination with a barrel, of a frame member having a cylindrical socket for receiving the end portion of said barrel, a spring and abutment in said barrel having a downwardly-extending lug, spaced flanges on said socket between which said lug is inserted, and a cross pin engaging apertures in said spaced flanges and having a bearing on said lug.

6. In a gun, a barrel telescopically engaging the frame and stock portion, a plunger within said barrel, a spring for said plunger, an abutment for said spring, mechanism for retracting said plunger and compressing said spring, said parts constituting an organized unit mounted on the barrel, and attachable and detachable as such from the frame.

7. A gun, comprising a stock, a sheet metal frame member secured to said stock and providing a cylindrical socket, a trigger and sear mounted in said frame, a barrel telescopically engaging said cylindrical socket, power storage mechanism mounted as an organized unit upon said barrel and attachable and detachable therewith from said cylindrical socket, and means for holding said barrel and frame in engagement, with said power storage mechanism in operative relation to said trigger and sear.

8. In a gun, the combination with a stock, of a frame formed of a U-shaped sheet metal member embracing and projecting forward from said stock, its upper portion constituting a cylindrical socket, a barrel telescopically engaging the cylindrical socket portion of said frame, a lever mechanism mounted as an organized unit on said barrel and insertable therewith between the sides of the U-shaped portion of said frame, and a pin engaging a bearing between said barrel and lever mechanism for retaining the barrel in engagement with said frame.

9. In a gun, the combination with a stock, of a frame formed of sheet metal fashioned to have a semi-cylindrical top portion, parallel side portions and inwardly and downwardly projecting portions forming a contracted downwardly-opening slot, a barrel telescopically engaging said frame and bearing against the cylindrical top portion thereof, a lever mechanism on said barrel extending in between said flanges, a securing pin passing through said frame intermediate said barrel and lever mechanism, and a bearing on said barrel for engagement with said pin to retain the barrel in engagement with said frame.

10. In a gun, the combination with a stock, of a frame formed of sheet metal having a semi-cylindrical top portion, parallel side portions and inwardly and downwardly extending flanges from the forward portion of said side portions forming a downwardly-

opening contracted slot, abutting flanges bent inward from said parallel side portions in rear of said downwardly-extending flanges and forming a bottom for the frame having an aperture therein, a barrel engaging the socket portion of said frame, a lever mechanism on said barrel engaging the space between said downwardly-extending flanges, a trigger in said frame extending through the slot in said abutting flanges and a trigger guard secured between said downwardly-extending flanges.

11. In a gun, the combination with a stock, of a frame formed of sheet metal bent to 15 form a semi-cylindrical top portion, parallel side portions and inwardly and downwardly bent flanges from the forward portions of said side portions, abutting flanges from the rear portions of said side portions 20 apertured for the passage of the trigger, and a trigger guard struck up from sheet metal having its forward portion embraced by said downwardly-extending flanges and its rear portion hooked for engagement with 25 an apertured bearing in said abutting flanges.

12. In a gun, a sheet metal frame portion having a rounded top, parallel sides and inwardly and downwardly bent flanges providing a contracted downwardly opening 30 slot, inwardly-bent abutting flanges in rear of said downwardly-extending flanges apertured for the passage of the trigger, a hollow trigger guard struck up from sheet 35 metal having its forward end embraced by said downwardly-extending flanges and its rear end having a hooked engagement with said abutting flanges, and upwardly-struck ears on the top of said frame forming a 40 bearing for the sight.

13. In a gun, the combination with a barrel, of power storage means, a guide extending longitudinally of said barrel with which said actuating member is slidably 45 engaged, and a hollow link connecting said actuating member with the power storage means, embracing and concealing said guide when in normal position.

14. In a gun, the combination with a barrel, of power storage means, an actuating member slidable longitudinally of said barrel, a guide upon which said actuating member is mounted, extending parallel to the longitudinal axis of said barrel, and a connection between said actuating member and power storage means embracing and concealing said guide in normal position.

15. In a gun, the combination with a barrel, of a power storage actuating member slidable longitudinally of said barrel, power storage mechanism, a guide arranged parallel to said barrel upon which said actuating member slides, a frame for said barrel having spaced downwardly-extending flanges, and a hollow connection between said ac-

tuating member and power storage mechanism embracing and concealing said guide, and in normal position forming a tapering extension of the frame.

16. In a gun, the combination with a barrel, of a power storage actuating member 76 slidable longitudinally of said barrel, a guide for said actuating member extending parallel to said barrel, and a hollow breakdown lever connection between said actuating 75 member and the mechanism actuated thereby, embracing and concealing said guide in normal position.

17. In a gun, the combination with a barrel, of a plunger therein, a spring for actuating said plunger, toggle levers for compressing said spring, an actuating member 80 slidable longitudinally of said barrel, and a guide for said actuating member parallel to said barrel, said toggle levers being hollow 85 and in normal position concealing said guide.

18. In a gun, the combination with a barrel and frame with which said barrel is telescopically engaged, of a spring within 90 said barrel, an abutment for said spring, and securing means for said barrel within 95 said frame engaging said abutment.

19. In a gun, the combination with a barrel, of a frame with which said barrel is telescopically engaged, a spring within said 95 barrel, an abutment for said spring having a downwardly-extending lug with a notched bearing therein, and a securing pin for said barrel in said frame engaging the notched bearing in said lug.

20. In a gun, the combination with a barrel, of a spring abutment insertible through a slot in one side of the barrel and having a lug projecting through the opposite side of said barrel, a frame with which 105 said barrel is telescopically engaged, and a securing pin for said barrel in said frame engaging said downwardly-extending lug on said abutment.

21. In a gun, the combination with a barrel, of a flat spring abutment insertible through a slot in one side of said barrel and having a shouldered engagement with an aperture in the opposite side thereof, and a bifurcated spring-compressing lever 115 embracing and pivotally secured to said abutment.

22. In a gun, the combination with a barrel, of a flat spring abutment insertible through an aperture in one side of said barrel, a spring-compressing lever pivoted to 120 said abutment and bifurcated to embrace the same, and a bifurcated plunger shank embracing said abutment and bifurcated lever.

23. In a gun, the combination with a barrel, of a flat spring abutment insertible through an aperture in one side of said barrel, a spring-compressing lever fulcrumed on said abutment, and a cross pin forming 130

the fulcrum for said lever and an anchor for said abutment.

24. In a gun, the combination with a barrel having intersecting longitudinal and cross slots in one side thereof, of a flat spring abutment insertible through one of said slots, a spring-compressing lever fulcrumed upon said abutment, and a pin forming the fulcrum for said lever extending 10 transversely through said abutment and engageable therewith in said intersecting slots.

25. In a gun, the combination with a barrel having intersecting longitudinal and cross slots in the upper side thereof, of a flat spring abutment insertible through the longitudinal slot, a bifurcated spring-compressing lever embracing said abutment and also engaging said longitudinal slot, and a cross pin forming a pivot for said lever and 15 anchor for said abutment engaging said cross slot.

26. In a gun, the combination with a barrel, having a longitudinal and a cross slot in the upper side thereof, of a flat spring 20 abutment insertible through said longitudi-

nal slot, a spring-compressing lever extending through a slot in the bottom of said barrel and bifurcated to embrace said abutment, and a pin forming a fulcrum for said lever and anchor for said abutment, extending 30 transversely therethrough and engaging said cross slot.

27. In a gun, the combination with a barrel, of a frame having a cylindrical socket for telescopically receiving the end portion 35 of the barrel, a tapered seat for the end of the barrel in said socket, a lug projecting downward from said barrel, spaced flanges in said socket member, between which said lug is inserted, and a tapered pin passing 40 through apertures in said spaced flanges and engaging a bearing on said lug to force the latter and the barrel to its tapered seat.

In testimony whereof I affix my signature in presence of two witnesses.

CHARLES F. LEFEVER.
